[57] CLAIM

The ornamental design for the main body of a fuel dispenser,
as shown and described.

DESCRIPTION

FIG. 1 is a front view of the main body of the fuel dispenser,
the rear view being a mirror image thereof, showing new
design;

FIG. 2 is a left side view thereof;

FIG. 3 is a right side view thereof;

FIG. 4 is a top view thereof;

FIG. 5 is a base view thereof; and,

FIG. 6 is a perspective view thereof in the state of the use.
